(57) **CLAIM**

The ornamental design for a lid opening mechanism for a
printer, as shown and described.

DESCRIPTION

FIG. 1 is a perspective view of a lid opening mechanism for
a printer, showing my design;

FIG. 2 is a front plan view thereof;

FIG. 3 is a rear plan view thereof;

FIG. 4 is a left side elevation view thereof;

FIG. 5 is a right side elevation view thereof;

FIG. 6 is a top side view thereof; and,

FIG. 7 is a bottom side view thereof.

The broken lines depict portions of the lid opening mechanism
for a printer that form no part of the claimed design.

1 Claim, 7 Drawing Sheets
